UNITED STATES PATENT OFFICE.

EUGEN REISZ, OF BERLIN-TREPTOW, GERMANY.

PROCESS TO INCREASE THE SENSIBILITY OF RELAYS FOR ALTERNATING CURRENTS.

1,234,489.

Specification of Letters Patent. Patented July 24, 1917.

Application filed April 9, 1913. Serial No. 760,004.

To all whom it may concern:

Be it known that I, EUGEN REISZ, a subject of the Emperor of Austria, residing at Berlin-Treptow, Germany, have invented 5 certain new and useful Improvements in Processes to Increase the Sensibility of Relays for Alternating Currents, of which the following is a specification.

This invention relates to a method of increasing the sensibility of relays for alternating currents of a determined number of periods so that the currents reinforced react directly or inductively upon the relays. In this connection, it is presumed that alternating currents with simple curve form, for instance, sine currents, are to be reinforced. The method can only be employed when the relay has no mechanical inertia at all, as is the case, for instance, in gas discharging 15 relays, as otherwise the self-oscillation of the apparatus would frustrate the effect just explained. In the drawing an apparatus is shown wherein the method may be effectively carried out, and therein an embodiment of the invention is represented in diagrammatic form.

Referring to the drawing, R is the relay consisting of a discharge tube D having a heated cathode K and an anode A between 30 which an auxiliary electrode H of sieve or net form is arranged. A battery B provides the heating current for the cathode and a second battery B¹ the current for the tube. The auxiliary electrode is connected to the 35 battery B by the adjustable resistance W¹. Two transformers T¹ and T² inductively connect the line N or other source of currents to be reinforced with the relay circuit and the latter circuit with the receiving 40 instrument J respectively. The transformer T¹ consists of three windings p¹, s¹ and t¹; the winding p¹ is the primary of the transformer and is connected with the source N of the currents to be reinforced, for instance 45 with the antenna; s¹ is the secondary winding cut into the circuit of the auxiliary electrode. The third winding t¹ of the transformer T¹ is arranged in the circuit which contains the anode A and the primary winding p² of the second transformer T². An 50 adjustable resistance W is furthermore arranged in this circuit and prevents the generation of a continuous alternating current in said circuit and at the same time regulates the current flowing through the discharge tube. The terminals of the second-

ary winding s² of the transformer T² and the receiving instrument J, for instance a telephone, are connected. The source of the alternating current to be reinforced acts 60 inductively through the auxiliary winding s¹, as above noted, upon the auxiliary electrode. The anode currents reinforceably released in this manner flow through the winding p² and induce currents in the telephone and through the winding t¹ again influence the auxiliary electrode whereby a further increase of the anode current results. When the electric constants of coils T¹ and T² are selected in such manner that the currents reacting upon the relay coincide in 65 their direction with the primary current, that is, when there is no shifting of phases present between the primary and secondary currents, then the amplitudes of the currents 70 reinforced by the relay always become greater. The strength of these currents can be adjusted through the non-inductive resistance W cut into the anode circuit to the desired value. The resistance W also prevents the appearance of a continuous alternating current through the mutual induction 75 of the windings s¹ and t¹.

The current i¹ coming from the line or other source of alternate current flows 85 through the winding p¹ of the transformer T¹ and induces similar currents in the windings t¹ and s¹. The impulses in the circuit through t¹ are so timed that the current in s¹ is continually augmented, or the current induced in s¹ is in phase with the current induced in s¹ from p¹. The two circuits through the tube R are in resonance with 90 each other and the capacity of the coils is relied upon to effect this tuning of the circuits. 95

What is claimed is:—

1. In a relay system comprising a relay without inertia, a line circuit, an actuating circuit for said relay containing the currents to be reinforced and a local relay circuit containing the reinforced currents, the two last-named circuits being adjusted to resonance, each of the circuits being provided with a winding and all the windings 105 acting inductively on the other windings.

2. In a relay system comprising a relay without inertia, a line circuit, an actuating circuit for said relay containing the currents to be reinforced and a relay circuit 110 containing the reinforced currents, means to establish resonance between the two last

2
named circuits, a transformer comprising a winding embodied in the relay circuit, a second winding embodied in the actuation circuit and a third winding embodied in the line circuit, all windings being capable of exercising an inductive action on the others, and a second transformer comprising a winding embodied in the relay circuit and a second winding connected with a receiving instrument.

3. In a relay system comprising a relay without inertia, a line circuit, an actuating circuit for said relay containing the currents to be reinforced and a relay circuit containing the reinforced currents, means to establish resonance between the two last named circuits, a transformer comprising a winding embodied in the actuating circuit of the relay and a second winding embodied in the relay circuit, both windings being capable of acting inductively on each other, the self-induction of both being so established that the currents induced in the first named winding by the other winding have a phase displacement of 90° relatively to the inducing currents.

4. In a relay system comprising a gas discharge relay having a cathode, an anode and an auxiliary electrode, a line circuit car-

rying alternating currents of simple curve 30 form, an actuating circuit for the relay connected with the auxiliary electrode of the same, and a relay circuit connected with the anode and cathode of the relay, means to establish resonance between the two last 35 named circuits, a transformer comprising a winding embodied in the line circuit, a second winding embodied in the circuit of the auxiliary electrode, and a third winding embodied in the circuit of the anode, all the 40 windings being arranged to act inductively on each other, the self-induction of the second and third of these windings being so established that the currents induced in the second winding by the current in the third 45 winding have a phase displacement of 90° relatively to the inducing currents and a second transformer comprising a winding embodied in the anode circuit and a winding connected with a receiving instrument. 50

In testimony whereof I have hereunto set my hand in presence of two subscribing witnesses.

EUGEN REISZ.
